[57] CLAIM

The ornamental design for a sign, as shown and described.

DESCRIPTION

FIG. 1 is a front perspective view of the sign according to my new design illustrating the base portion with the signage plate removed;

FIG. 2 is a front perspective view similar to FIG. 1 except the signage plate is illustrated in an exploded arrangement;

FIG. 3 is a front elevational view thereof;

FIG. 4 is a sectional view taken along lines 4—4 as shown in FIG. 3; and,

FIG. 5 is a sectional view taken along line 5—5 as shown in FIG. 3.
